UNITED STATES PATENT OFFICE.

DANIEL ILIFFE, OF SOMERVILLE, MASSACHUSETTS.

LIFTER FOR SASHES OF GREENHOUSES AND THE LIKE.

982,500.

Specification of Letters Patent. Patented Jan. 24, 1911.

Application filed March 20, 1908. Serial No. 422,249.

To all whom it may concern:

Be it known that I, DANIEL ILIFFE, a citizen of the United States, and a resident of Somerville, in the county of Middlesex and State of Massachusetts, have invented an Improvement in Lifters for Sashes of Greenhouses and the Like, of which the following description, in connection with the accompanying drawing, is a specification, like letters on the drawing representing like parts.

This invention relates to a device for operating a sash, and by that it is intended to mean that the device is for the purpose of opening and closing entirely or partially a hinged or otherwise movable sash, skylight, transom, or other similar object.

It is the object of this device to provide a mechanism which will act positively to secure the desired movement of the shaft, which will hold the same locked in the position to which it is set, which will be strong and durable, and which may be operated from any desired point, irrespective of the position of the mechanism connected directly with the sash, and which will take up the minimum amount of space, especially in so far as the parts for transmitting the power are concerned.

The invention is particularly designed for use in connection with the raising and lowering of skylights in greenhouses, but it is obvious that it is equally useful for many other purposes.

The nature of the invention will more fully appear from the accompanying description and drawings and it will be particularly pointed out in the claims.

The drawings illustrate the preferred form of the device as adapted for use in a greenhouse.

In the drawings, Figure 1 represents an illustrative view in cross section of a portion of a greenhouse showing the device in position and connected to a skylight which has been raised and is held raised thereby. Fig. 2 is a top plan view of the supporting bracket and connected parts of the device. Fig. 3 is a side elevation of the parts shown in Fig. 2. Fig. 4 is a front elevation of a portion of a sash-operating shaft and the upper portion of the device of this invention by which it is operated.

The outline of the portion of the walls and roof of a greenhouse or other similar structure is represented at A, and a skylight or sash B is shown pivoted to the roof at B², but this arrangement is simply for the pur-

poses of illustrating one adaptation of the device of the invention.

A suitable shaft C is supported in any suitable manner adjacent the sash or sashes to be operated, and is provided at suitable intervals with suitable connections to the sash or sashes by which, upon the rotation of the shaft in opposite directions the sash or sashes will be correspondingly raised or lowered. Such connections are indicated as a crank arm C² on the shaft and a link C³ extending from the crank arm to the sash.

The pulley D is mounted on and made fast to the shaft C at any suitable point. Herein the pulley D is shown as mounted between a forked arm D² of a support for the shaft C mounted on the end of the upright D³.

A supporting bracket E is firmly mounted at any desired point where it will be convenient to locate the means for operating the device. The bracket E is shown as provided with an aperture E², adapted to fit over a post and be held in place by a setscrew E³, but any suitable means may be employed for holding the bracket in position. The bracket E has journaled therein a rotatable drum F, preferably spirally grooved on its periphery, as shown. Means are also located on the bracket by which the drum may be rotated in either direction, and also locked when desired against rotation. A simple and efficient means for securing this end is shown and comprises a worm wheel G, mounted on the end of the shaft of the drum F, and a worm G² engaging the worm wheel G and mounted transversely thereof in arms G³, forming a portion of the bracket E. The shaft of the worm is provided with a suitable operating hand-wheel G⁴. A cord H is wound about the drum F in the spiral groove for several turns, and then the ends of the cord pass up and around the pulley D, in opposite directions, and are fastened to the pulley as indicated in Fig. 4.

By the term "cord" it is intended to include any flexible device, such as rope, wire rope, wire, chain, or other suitable connection, but wire rope is preferred because of its strength, flexibility, wearing qualities and comparatively small size.

Idler pulleys are arranged at suitable points to change the direction of the cord, and in the drawing two sets are shown, one set at K and another at L in Fig. 1, but any

number may be employed according to the 5 number of changes in the direction of the cord made necessary by the particular conditions. Preferably one of these sets will be located in the bracket E, wherein the shaft M is shown as mounted in the bracket and the idler pulleys N are mounted thereon so as to rotate and move sidewise as the 10 cord winds and unwinds on the spiral drum F.

The bracket E may be adjusted on its support by set-screw E³ so as to take up any slack existing in the cord and insure a direct and positive operation of the pulley B. 15 It will thus be seen upon turning the hand-wheel G⁴ the rotation of the drum F will be transmitted directly to the pulley D, and thence to the shaft C, and the latter will be turned in one or the other direction 20 to open and close the sash. When the hand-wheel is not being moved the worm G² interlocking with the worm wheel G prevents any rotation of the drum F. The flexibility of the cord by which the power is transmitted from the drum to the pulley enables 25 the bracket E, with the operating hand-wheel G, to be placed in any desired position in the building.

Having described my invention, what I 30 claim as new and desire to secure by Letters Patent, is:

1. A sash operating device comprising a 35 pulley and its intermediate connections for raising the lowering the sash upon rotation thereof is one or the other direction, a bracket, a drum journaled in said bracket, a cord wound about said drum and having its ends passed in opposite directions around and fastened to said pulley, means for ro-

tating the drum in either direction and for 40 locking it against rotation.

2. A sash operating device comprising a 45 pulley and its intermediate connections for raising and lowering the sash upon rotation thereof in one or the other direction, a bracket, a drum journaled in said bracket, a cord wound about said drum and having its ends passed in opposite directions around and fastened to said pulley, means for rotating the drum in either direction and for 50 locking it against rotation, and idler pulleys arranged in pairs to guide and change the direction of said cord whereby the said support may be located at any desired point irrespective of the location of the said shaft. 55

3. A sash operating device comprising a 60 pulley and its intermediate connections for raising and lowering the sash upon rotation thereof in one or the other direction, a bracket, a drum spirally grooved on its periphery and journaled in said bracket, a shaft mounted in said bracket parallel with said drum, a pair of idler pulleys mounted on said shaft to rotate and slide freely thereon, a cord wound about said drum in said 65 spiral groove passing under said idler pulleys and having its ends passed in opposite directions around and fastened to said pulley, and means for rotating the drum in either direction and for locking it against 70 rotation.

In testimony whereof, I have signed my name to this specification, in the presence of two subscribing witnesses.

DANIEL ILIFFE.

Witnesses:

MABEL PARTELOW,
THOMAS J. DRUMMOND.

Corrections in Letters Patent No. 982,500

It is hereby certified that in Letters Patent No. 982,500, granted January 24, 1911, upon the application of Daniel Iliffe, of Somerville, Massachusetts, for an improvement in "Lifters for Sashes of Greenhouses and the Like," errors appear requiring correction as follows: Page 2, line 34, the article "the," first occurrence, should read *and*, and same page, line 35, the word "is" should read *in*; and that the said Letters Patent should be read with these corrections therein that the same may conform to the record of the case in the Patent Office.

Signed and sealed this 21st day of February, A. D. 1911.

[SEAL.]

E. B. MOORE,
Commissioner of Patents.
